(57) **CLAIM**

The ornamental design for a bowl, as shown and described.

DESCRIPTION

FIG. 1 is a top plan view of a bowl showing our new design; FIG. 2 is a side elevational view thereof, all sides being the same;

FIG. 3 is a top plan view of a bowl showing a second embodiment of my new design;

FIG. 4 is a side elevational view thereof, all sides being the same;

FIG. 5 is a top plan view of a bowl showing a third embodiment of my new design;

FIG. 6 is a side elevational view thereof, all sides being the same;

FIG. 7 is a side elevational view of a bowl showing a fourth embodiment of my new design, all sides being the same;

FIG. 8 is a side elevational view of a bowl showing a fifth embodiment of my new design, all sides being the same; and,

FIG. 9 is a side elevational view of a bowl showing a sixth embodiment of my new design, all sides being the same.

The broken lines of a base and rim in the drawings are for illustrative purposes only and form no part of the claimed design.
